[57] CLAIM

The ornamental design for a flexible hose end cap, as shown and described.

DESCRIPTION

FIG. 1 is a front perspective view of a flexible hose end cap embodying my design;

FIG. 2 is a front elevational view of the flexible hose end cap as shown in FIG. 1, the rear view being a mirror image thereof;

FIG. 3 is a bottom plan view of the flexible hose end cap as shown in FIG. 1; and,

FIG. 4 is a top plan view thereof.

FIG. 4

FIG. 2

FIG. 3

FIG. 1
